UNITED STATES PATENT OFFICE.

JAMES OAG AND JOHN McDONALD, OF TORONTO, CANADA.

DRIVING-GEAR FOR BICYCLES.

SPECIFICATION forming part of Letters Patent No. 578,260, dated March 2, 1897.

Application filed May 8, 1896. Serial No. 590,742. (No model.)

To all whom it may concern:

Be it known that we, JAMES OAG, blacksmith, and JOHN McDONALD, machinist, of the city of Toronto, in the county of York and 5 Province of Ontario, Canada, have invented a certain new and Improved Driving-Gear for Bicycles, of which the following is a specification.

The object of our invention is to devise a 10 crank-and-lever driving-gear for bicyclists in which the possibility of sticking on a dead-center is obviated; and it consists, essentially, of a bent lever pivoted on the frame, its long arm having a pedal connected thereto 15 and its short arm connected by a pitman to a crank on the axle of the ordinary driving sprocket-wheel of the bicycle, a buffer being so connected to the long arm of the lever as to come into contact with the pitman when 20 the crank is on a dead-center and so throw it over the center, substantially as hereinafter more particularly described and then definitely claimed.

Figure 1 is a side view of a bicycle provided 25 with our improved driving-gear. Fig. 2 is an enlarged detail and side elevation of the driving-gear, showing the crank passing over the dead-center. Fig. 3 is a detail in elevation of the spring-buffer.

30 In the drawings like letters of reference indicate corresponding parts in the different figures.

A is a bent lever pivoted at *a* to the frame of the bicycle. To the long arm B of this lever is connected the pedal *b*.

C is the short arm of the lever, to which is pivoted one end of the pitman D, the other end of the said pitman being journaled on the crank E, which is fast on the axle of the 40 ordinary driving sprocket-wheel F of the bicycle. This sprocket-wheel is geared in the ordinary manner to the rear wheel of the bicycle, as indicated.

Although we speak of a separate crank-arm 45 being provided on the axle of the sprocket-wheel F, yet a wrist-pin on one of the spokes of the sprocket-wheel would answer the purpose of our invention, the separate crank-arm being only necessary on the other side of the 50 frame, where of course all the driving parts are duplicated.

G is a bolt adapted to slide through the lug

H on the long arm B of the bent lever. This bolt is held from dropping out by means of the pin *c*. Between the head of the bolt G 55 and the lug H is a coil-spring I. From this construction it will be seen that the bolt G and its connections form a spring-buffer which will yield to pressure and will regain its original position when the pressure is removed. 60

As shown in Fig. 2, when the cranks E are on the dead-center the end of the bolt G comes in contact with the pitman D and thus applies a yielding pressure to it to throw the 65 crank over the dead-center. Of course if the position of the bolts G were very accurately determined it might be possible to dispense with the coil-spring I; but in practice it is found preferable to use the spring, as jarring 70 of any kind is thus obviated. We consider this buffer a most important feature of our invention, as in practice it is found, especially when starting, that there is great danger of the cranks striking on the dead-center and 75 of the rider, by pressure on the pedals, bending or otherwise damaging the frame of the bicycle. When the buffers are used, however, the down lever just nicely starts the cranks off the dead-center, and the rider is 80 enabled to tell by the feel of the mechanism when it is safe to apply all his power on the downstroke of the other lever.

As it is desirable to change the gear of the bicycle to suit different riders or to suit different conditions of roads under which the bicycle is to be ridden, we provide the short arm *c* of the bent lever *a* with a series of holes, in any one of which the pitman D may be pivoted. 90

From the above description it will be seen that we have invented a very simple and effective up-and-down driving-gear for bicycles in which no toothed wheels or ratchets are used and in which no springs are required to 95 return the levers to their raised position after a stroke of the foot. It will also be seen that we have invented a very effective method of preventing all danger of the gear striking on the dead-center and thus rendering the bicycle liable to injury. 100

It should be mentioned that the nature of the spring-buffer is immaterial, as a rubber block, a flat spring, or any other form of

spring might be used instead of the spring-bolt shown.

What we claim as our invention is—

In a bicycle, the combination with the bent lever A, pivoted to the frame of the bicycle; the pedal b connected to the long arm B of the bent lever; the crank E connected with the axle of the driving sprocket-wheel F of the ordinary gearing; and the pitman D connecting the said crank with the short arm C of the bent lever and situated under said bent lever; of a buffer connected with the

long arm of said bent lever and constructed and arranged to come into contact with the pitman D and throw the crank over the dead-center when the said bent lever approaches the said pitman, substantially as and for the purpose specified. 15

Toronto, April 30, 1896.

JAMES OAG.

JOHN McDONALD.
